Primary Examiner — Bao-Yen T Nguyen

(57) **CLAIM**

The ornamental design for a display screen with graphical user interface, as shown and described.

DESCRIPTION

The FIGURE is a front view of a display screen with graphical user interface, showing my new design.

The outer broken lines showing the display screen form no part of the claimed design. The remaining broken lines showing numbers and portions of the graphical user interface form no part of the claimed design.

1 Claim, 1 Drawing Sheet
